UNITED STATES PATENT OFFICE.

DONALD M. SIMONS, OF OSBORNE, PENNSYLVANIA, ASSIGNOR TO STANDARD UNDER-GROUND CABLE COMPANY, OF PITTSBURGH, PENNSYLVANIA, A CORPORATION OF PENNSYLVANIA.

CABLE-JOINT STRUCTURE.

Application filed January 13, 1926. Serial No. 80,971.

In Letters Patent of the United States No. 1,585,124, granted on my application May 18, 1926, I have described a joint for electric cables intended for high-tension service. 5 The joint includes a body of insulating material formed of a single sheet of paper or like material, wrapped in a single continuous spiral around the united conductors and upon the adjacent ends of the bodies of machine-laid insulation, previously cut away to admit of electrical union of the conductors. The sheet of material carries at or near its edge metal strips which converge in the length of the sheet one toward another. In 10 the finished article these strips constitute screens electrically continuous with the cable sheath and flaring within the joint casing, and these screens are stress-limiting elements, relieving the spaces and the space-filling substances within the joint casing and external to the screens of all electrical stress. In an application filed August 5, 1925, Serial No. 48,301, I have described such a wrap within a cable joint, formed of a single sheet 15 of paper or other insulating material, filling the space between the cut-away ends of machine-laid insulation, and building out the body at the point of union, to the normal diameter of the insulated conductor. And 20 I have further shown in this second application that the sheet may be of such length and proportions that it may in continuous wrap constitute not merely a building-out and a replacement of the machine-laid insulation, 25 where the latter had been cut away to admit of union between the bared conductor ends, but it may constitute also the body of insulation within the joint casing, external 30 to the normal diameter of the insulated cable conductor, and carrying at its ends the flaring screens of the application first above mentioned.

In the development of the art of joint-making for high-tension service a particular form of electric union has been found most serviceable, and I have discovered that by applying to the form of union to which I here allude a body of insulation built of sheet material laid in a single spiral wrap (and ordinarily filled at the time of wrapping, or subsequently, with insulating oil or other insulating liquid) I obtain a joint which is in highest degree effective and secure.

My invention is illustrated in the accompanying drawings, in which the figure is a view in longitudinal and axial section of a joint in the building of which my invention is practiced.

Referring to the drawing, here are shown two cable-ends from which the lead sheath 1 has been cut away, exposing the envelopes 2 of machine-laid insulation, and from which the envelopes of insulation in turn have been cut away, exposing the conductors 3. The insulation is cut away in opposite successions of steps. The bodies of insulation are cut away in the lowest steps in re-entrant recesses 20, and electric union of the bared cable ends is effected by means of a body 4 of metal which makes electric union upon the bared conductor ends 3, which fills the reentrant recesses 20 in the bodies of insulation, and which presents an exposed surface 41 flush with the surface 21 of the lowest step of insulation. It is no part of my present invention, how the body 4 is formed and applied. The art knows that it may be formed of low-fusion metal, cast to place, and it knows that it may be preformed and sweated to place and to electric union upon the conductor ends. When the uniting body 4 has been applied, its exposed cylindrical surface 41 is continuous with the cylindrical surface 21 of the lowest step of insulation 2.

I have discovered that by wrapping upon the union so effected the web of insulating material which I have described in my earlier applications and alluded to above I obtain a joint of hitherto unattained excellence.

The sheet is a web of such width as to extend between the next pair of steps, from riser 22 to opposite riser, so that as it is wrapped on in one continuous spiral it fills all the space between the steps. The sheet itself is of increasing width correspondingly stepped, so as to fill all the space between the opposite cut-away ends of machine-laid insulation. Thus a body 8 is built up which, filling all the interval, restores the original diameter of the insulated conductor throughout the extent of the joint. The sheet of wrapped-on material may be continuous in length throughout all the spiral extent, or it may be pieced in a succession of lengths; but in width it extends without break from

2
face to face of the cut-away bodies of insulation.

The material of which the sheet is composed will ordinarily be paper; muslin may be used, or other equivalent material. It will ordinarily at the time of application be already filled with oil, varnish, or other suitable filling material. The wrapping may be done under oil. I have, however, discovered 10 an alternative method, well suited to the conditions of field installation, and which affords a satisfactory result. It is this: As wrapping progresses the advancing line of contact with the surface to which application is made is flushed with oil or equivalent material, poured upon it. Eventually the otherwise finished joint will be flushed with oil or equivalent material.

When the web has been applied and the 20 interval between the bodies 2 of insulation has been filled in the manner described, the joint may be completed as desired. The whole is enclosed in the usual joint casing 5, secured at its ends to the cable sheath 1. At 25 any suitable time before completion, the joint structure may be flushed and filled with oil, or other insulation in liquid condition. And in the finished joint I prefer that the joint casing 5 shall carry a reservoir full 30 of liquid insulation, in the form of a closed length of sylphon tube 50 communicating with the chamber within the casing. This in the manner and for the purposes known to the art.

35 The wrapping which I have described may built the body 8 and no more. Preferably, however, I continue the wrap beyond the point where the original diameter of the cable insulation is restored, and in continued 40 wrap I similarly fill, first the space between the cut-away ends of the cable sheath, and then I similarly and in continuous wrap (with the possibility of piecing longitudinally, as already explained) build up an 45 overlying and enveloping body 9, which body 9, in consequence of metallization of the web of paper adjacent its opposite edges, carries flaring metallic screens 10, intimately 50 contacting with the substance of body 9, electrically united with the ends of the cable sheath 1, limiting the region of electrical

strain, and relieving the spaces and materials within the joint casing and external to the screens of such strain. It will be understood that in order to build the body 9 having the characteristics described, the web of paper will be suitably proportioned, its width being increased at the proper points and to the proper extent, and the metallization will be effected in suitable manner and 60 over suitably disposed areas.

55 It will be understood that cable joints must ordinarily be made in the field, and the fact will be appreciated by those acquainted with the industry, that my invention is 65 adapted to field conditions, that it may be advantageously and successfully practiced.

I claim as my invention:

In a joint structure for an electric cable two meeting cable-ends including each a 70 conductor, an enveloping body of machine-laid insulation, and a sheath, the body of machine-laid insulation being cut back in a stepped cut and leaving the conductor-end unenveloped, the insulation adjacent the 75 conductor-end being recessed with a re-entrant conical recess, a body of conducting material uniting the conductor-ends, filling the re-entrant recesses in the ends of the bodies of machine-laid insulation, and presenting a continuous surface with the lowest 80 step of the cut-away ends of machine-laid insulation, and a wrapped-on body of sheet insulation overlying the continuous surfaces of machine-laid insulation and of the unit- 85 ing body, and all the space external to the uniting body and between the steps of the cut-away envelopes of insulation, said wrapped-on body being formed of a web of material of the full width of the wrap and 90 said wrap continuing beyond the restoration of the original diameter of machine-laid insulation and in such continued portion carrying strips of metal which when wrapping is completed constitute flaring screens of 95 metal electrically continuous with the ends of the cable sheath and borne in intimate union upon the wrapped-on body of insulation.

100 In testimony whereof I have hereunto set my hand.

DONALD M. SIMONS.
